UNITED STATES PATENT OFFICE.

THEODORE A. HARRIS, OF NEW YORK, N. Y.

SOUND-REPRODUCING DEVICE.

Application filed January 8, 1927. Serial No. 159,795.

My present invention relates generally to sound reproducing devices, and has particular reference to a device designed for joint employment with a phonograph and an independent energy source such as a radio.

It has been found desirable from various standpoints to associate radios with phonographs, and it is one object of the present invention to provide a device which will render this mutual association more intimate and at the same time highly efficient and economical.

Briefly, my invention contemplates the provision of a device wherein a single diaphragm may be employed selectively either as the diaphragm which is responsive to the impressions of a phonograph record, or as the diaphragm which is responsive to the energy fluctuations of a radio reproducing unit. More particularly, it is an object of the present invention to provide a device wherein the diaphragm which is normally associated with the usual phonograph sound box may itself be rendered responsive to the source of energy transmitted by a radio or similar device.

One feature of my invention lies in providing a device which comprises, in part, a phonograph sound box of substantially ordinary construction and arrangement, this sound box being normally useable by itself in the usual manner; and which comprises a reproducing unit typified by the usual electromagnetic radio units, the last mentioned unit being so constructed and arranged, and being so associated with the sound box that the diaphragm of the latter may under desired circumstances be made to serve as the diaphragm of the radio unit.

It is a feature of my invention to provide a mutual arrangement of sound box and radio unit wherein these elements are relatively movable or adjustable, and wherein means are provided for causing the removable association hereinbefore mentioned.

In one form of the invention, I may advantageously provide a vibratable element in the form of a pin or the like in association with the radio unit; and in such an event, the sound box diaphragm may be provided with means for removably receiv-

ing said pin in much the same manner that the usual phonograph needle is received.

In one embodiment, a phonograph sound box is mounted in usual manner upon a tone arm, and the latter, together with the sound box, is rendered freely movable and adjustable in the wellknown ordinary manner. I have taken advantage of this ordinary movability of the tone arm and sound box by providing a radio unit in association with the phonograph and in such positional relation with respect to the sound box that a predetermined movement of the latter will bring the sound box and the unit into close proximity; means being provided for thereupon causing the desired removable association between the unit and the sound box.

In other forms of the invention, the radio unit is associated with the sound box in such a manner as to be normally carried with the latter as the sound box is employed in its usual manner with phonograph records. In embodiments of this character, means are provided for permitting normal dissociation of the unit and the sound box, while at the same time rendering it possible to removably associate the radio unit in the desired manner with the diaphragm of the sound box.

Other objects of my invention lie in the provision of a simple, rugged, yet highly efficient device whose manufacture is inexpensive and whose manipulation requires no particular skill. With these objects in view, certain features of my invention lie in the particular arrangement and construction of parts which render the device as a whole compact, of good appearance, devoid of complicated and unnecessary parts, and reliable and efficient in operation.

For the attainment of the foregoing objects and such other objects as may hereinafter appear or be pointed out, I have illustrated several forms of my invention in the accompanying drawings in which—

Fig. 1 is a plan view of a phonograph tone arm associated with a phonograph device which embodies my invention;

Fig. 2 is an enlarged front elevational view of a portion of the device shown in Fig. 1; parts of the phonograph sound box

being broken away for the sake of clearness;

Fig. 3 is a front elevational view similar to Fig. 2 showing a modification; a portion of this Figure being broken away to reveal the interior;

Fig. 4 is a plan view of the device shown in Fig. 3;

Fig. 5 is a view similar to Figs. 2 and 3 showing another modification;

Fig. 6 is a cross-sectional view taken substantially along the line 6—6 of Fig. 5; and

Fig. 7 is a fragmentary cross-sectional view taken substantially along the line 7—7 of Fig. 6.

Referring to the drawings and particularly to Figs. 1 and 2, it will be observed that I have shown a phonograph device of usual construction, including side walls 10, a cover or table 11, a rotatable record support 12, and a phonograph tone arm 13. The latter has been shown as emanating from an opening 14 in one corner of the table 11, and as being pivotal about this corner for the purpose of permitting the sound box 15 to travel in a radial direction with respect to the turntable 12.

In accordance with the present invention, I provide a radio unit 16 in fixed association with the phonograph device, the particular embodiment of Fig. 1 showing a radio unit mounted adjacent to the right-hand side wall 10 with the conducting wires 17 extending rearwardly and thence down through the table 11 to the radio device proper.

The unit 16 is so mounted that a swinging movement of the tone arm 13 into a position substantially indicated by dotted lines will bring the sound box 15 into relatively close proximity, and in fact axial alignment, with the unit 16. It may be briefly noted at this point that in accordance with my invention, the sound box 15 and the tone arm 13 may be normally employed in their usual manner, but may when desired be swung into the dotted line position wherein a removable association may be made between the sound box 15 and the unit 16.

Referring now to Fig. 2, it will be observed that I have shown a sound box embodying a diaphragm 18 which may be of any usual type and construction; this diaphragm being mounted and supported in a usual manner. Securely attached to the mid-point of the diaphragm 18 is a lever arm 19 associated at its outer end with a needle receptacle 20 of usual construction. In the positional relation shown in Fig. 2, the sound box 15 has been rotated about its axis to position the needle receptacle 20 upwardly, the latter being illustratively shown as containing a regular phonograph needle 21 held in position by means of a set screw or the like 22.

At its inner end, the lever 19 is integral with, or rigidly associated with an axial

portion which is soldered or similarly fixed to the center portion of the diaphragm 18. This axial portion is provided with a cup-shaped receptacle 23 similar to the receptacle 20 but having its opening aligned with the axis of the diaphragm. This receptacle 23 may be provided with a set screw 24 or the like, and is preferably provided with an interior bore which flares outwardly at its outer end.

The radio unit 16 will generally embody an electromagnet, and in the form shown, the electromagnet is associated with an armature to which an outwardly projecting axial needle 25 is rigidly attached. The invention contemplates that the needle 25 will vibrate axially when the radio unit 16 is set into operation for electrically transmitting sound.

Reference to Fig. 2 will show how the outwardly projecting element 25 may be securely positioned within the receptacle 23. This positioning may be made to take place by simply swinging the tone arm 13 into the position which axially aligns the vibrating element 25 and the diaphragm 18. The flaring construction of the opening in the receptacle 23 will prevent accidental breakage of the projecting element 25, in case the tone arm is swung with too great violence, or in case the contemplated axial alignment has become maladjusted.

Although I have shown a sound box which is rotatable about its axis for the purpose of removing the needle 21 from proximity with the turn-table 12, nevertheless it will be understood that as to certain phases of my invention, the employment of such a sound box is not essential. Whatever the character of the sound box, it will be clear that the radio unit 16 will have a positional mounting and relationship so that the association between the element 25 and the receptacle 23 may be rendered possible. It will also be understood that if desired, the receptacle 23 may be mounted upon the element 25, in which case a corresponding pin or needle will be integrally associated with the diaphragm 18.

In Figs. 3 and 4, I have shown a modified form of the invention wherein the radio unit is arranged and constructed to travel with the sound box during the normal utilization of the latter. I have shown a radio unit 26 axially aligned with a sound box 27, and mounted within an outwardly extended skirt or sleeve 28 carried by the sound box. The mounting of the radio unit 26 may advantageously be made in such a manner as to permit axial movement of the unit with respect to the sound box 27. It will be observed that I have shown an inclined slot 29 provided in the sleeve 28, and a pin 30 carried by the unit 26 and extending outwardly through the slot 29. I have also shown a

hand grip or knob 31 carried by the unit 26, and it will be obvious that rotation of the knob 31 will cause the walls of the slot 29 to effect an inward axial movement of the unit 26.

In this form, I have shown a cup-shaped receptacle 32 associated with an element or pin 33 extending outwardly from the unit 26. The receptacle 32 corresponds to the receptacle 23 of Fig. 2, and the projecting element 33 will be rigidly associated with a vibratable armature, the same as the element 25 of Fig. 2. I have also shown a set screw 34 corresponding to the set screw 24 but of longer construction to permit its manipulation from the exterior of the sleeve 28.

The employment of the device shown in Figs. 3 and 4 will be understood from the description given. A slight adjustment of 20 the set screw 34, and a mere turning of the knob 31 will either separate or mutually associate the diaphragm of the sound box 27 and the vibratable pin 33 of the radio unit 26. Suitable counterbalancing means (not 25 shown) may be provided for compensating for the added weight of the unit 26 when the sound box is employed in usual association with phonograph records.

In Figs. 5, 6, and 7 I have illustrated a 30 modified form wherein the relative movement of the radio unit is one which is arcuate rather than axial. In this form I have provided a substantially flat locking disc 35 in integral association with the diaphragm 36. 35 The disc 35 lies in a plane substantially parallel to the diaphragm 36, and is provided with a keyhole slot 37. The disc is preferably associated with the diaphragm by means of two diverging supports 38 extending outwardly from the axial portion 39 which is fixedly associated with the diaphragm 36.

In this embodiment, the radio unit is pivotally supported at one side thereof, as 40 shown at 40 in Fig. 6. Almost diametrically opposite to the pivotal support is an extension 41 terminating in a pin 42 which extends outwardly through a slot 43 in an enclosing sleeve 44. The latter sleeve corresponds substantially to the sleeve 28 of 45 Figs. 3 and 4, and by threading the pin 42 and mounting thereon a knurled nut 45 of greater diameter than the width of the slot 43, it is possible to position the radio unit 50 in either of two extreme pivotal positions.

In this form of the invention, the projecting element 46 which corresponds to the elements 25 and 33 previously described, terminates in a pair of spaced and juxtaposed 55 wedging enlargements 47. The diameters of the latter are smaller than the diameter of the largest portion of the slot 37, whereas the space between them is substantially equal to the thickness of the disc 35. By manipulation of the nut 45, the radio unit may be

positioned in either of two positions. In one thereof, the enlargements 47 will frictionally engage the disc 35 and the association between the unit and the diaphragm will be complete. In the other position, the 70 enlargements 47 will lie free within the large portion of the slot 37 and the diaphragm will then be vibratable independently of the radio unit.

The slot 37 is preferably so arranged that 75 the weight of the radio unit itself will position the enlargements 47 in their proper places. Thus, when the sound box has been turned up as in Fig. 6, with the phonograph needle at the top, fixed association between 80 the projection 46 and the diaphragm 36 will be effected when the pin 42 lies at the lower end of the slot 43. Similarly, when the sound box is turned so that the phonograph 85 needle is at the bottom, in contemplation of normal usage of the phonograph diaphragm, the pin 42 will again lie at the bottom of the slot 38. In this way, the nut 45 will be compelled to do a minimum of work, and will 90 not have to function to support the radio unit against its own weight.

It will thus be seen that I have shown a 95 device which is extremely simple, yet highly desirable, compact, and efficient. The several embodiments have been shown for purposes of illustration, and I do not mean to limit myself to any particular form except in so far as I may be compelled to do so by prior art of which I am not now aware. In 100 its essence, it will be observed that my invention resides in the employment of the usual phonograph diaphragm as the diaphragm which may be made to respond to the energy variations of the radio unit. My 105 invention provides means for accomplishing this purpose in a simple and expeditious manner, no manipulations other than the mere turning or adjusting of a set screw or the like being necessary.

The numerous advantages of my construction need hardly be pointed out, a great saving being effected by the mere elimination of any separate radio diaphragm itself. Furthermore, the advantages of the usual 110 phonograph horn are rendered available for radio purposes, and particularly where the horn is of the newly developed long type at present considered highly desirable, the employment of my invention will be of particular advantage to radio users.

It will be understood that the unit typified by the units 16, 26, etc., may under certain circumstances be one which is not necessarily associated with a radio device. It 115 will also be understood that the provision of a projecting pin or element typified by the elements 25, 33, and 46 may under certain circumstances be unnecessary.

It will be obvious that many other changes 120 in the details herein described and illus-

trated for the purpose of explaining the nature of my invention may be made by those skilled in the art without departing from the spirit and scope of the invention 5 as expressed in the appended claims. It is therefore intended that these details be interpreted as illustrative and not in a limiting sense.

Having thus described my invention and 10 illustrated its use, what I claim as new and desire to secure by Letters Patent is—

1. In a device of the character described, in combination, a pivotal phonograph tone arm, a sound box carried by the end thereof 15 and including a vibratable diaphragm, an independent reproducing unit including a vibratable element, said unit being so mounted and positioned as (a) to permit normal utilization of the tone arm and sound box 20 and (b) to be encountered by the sound box after a predetermined pivotal movement of the tone arm, and means for removably securing the diaphragm and the vibratable element together when said encounter has 25 been effected.

2. In a device of the character described, in combination, a pivotal phonograph tone arm, a sound box carried by the end thereof and including a vibratable diaphragm, an 30 independent reproducing unit including a vibratable element, said unit being so mounted and positioned as (a) to permit normal utilization of the tone arm and sound box and (b) to be encountered by the sound box 35 after a predetermined pivotal movement of the tone arm, and means for removably securing the diaphragm and the vibratable element together when said encounter has 40 been effected, said means including complementary fastening elements carried by the diaphragm and the element respectively and positioned so as to permit cooperation thereof after said encounter has been effected.

3. In a device of the character described, 45 a pivotally mounted phonograph tone arm, a sound box carried at the end thereof and including a vibratable diaphragm, an attaching portion carried by and extending outwardly from the center of the diaphragm, and an independent reproducing 50 unit responsive to electrically transmitted sound and including a vibratable pin, said unit being so positioned and mounted with respect to said tone arm that when the latter is swung in a predetermined manner the 55 pin will be brought into substantial alignment and encounter with said attaching portion.

4. In a device of the character described,

in combination, a movable phonograph tone 60 arm, a sound box carried thereby and including a vibratable diaphragm, an independent reproducing unit including a vibratable element, said unit being so mounted and positioned as (a) to permit normal 65 utilization of the tone arm and sound box, and (b) to be approached by the sound box after a predetermined movement of the tone arm, and means for removably securing the diaphragm and the vibratable element together when said approach has been effected.

5. In a device of the character described, in combination, a movable phonograph tone arm, a sound box carried thereby and including a vibratable diaphragm and a needle 75 arm associated therewith, an independent reproducing unit including a vibratable element, said unit being so mounted and positioned as (a) to permit normal utilization of the tone arm and sound box, and (b) to be approached by the sound box after a predetermined movement of the tone arm, and means for removably securing said needle arm and said vibratable element to one another when said approach has been effected.

6. In a device of the character described, in combination, a movable phonograph tone arm, a sound box carried thereby and including a vibratable diaphragm and a needle arm associated therewith, an independent reproducing unit including a vibratable element, said unit being so mounted and positioned as (a) to permit normal utilization of the tone arm and sound box, and (b) to be approached by the sound box 90 after a predetermined movement of the tone arm, and means for removably securing said needle arm and said vibratable element to one another when said approach has been effected, said means including complementary 95 fastening elements carried by the needle arm and the element respectively and positioned so as to permit cooperation thereof after said approach has been effected.

7. In a device of the character described, 100 the combination with a phonograph sound box including a vibratable diaphragm, of an independent reproducing unit including a vibratable element, and means for removably securing said element to said diaphragm, said means comprising a pin, a sleeve adapted to encircle said pin, and a clamping device for securely holding the pin within said sleeve.

In witness whereof, I have signed this 115 specification this 29 day of December, 1926.

THEODORE A. HARRIS.
